UNITED STATES PATENT OFFICE.

ERNEST DU PONT, OF WILMINGTON, DELAWARE, ASSIGNOR, BY DIRECT AND MESNE ASSIGNMENTS, TO BALL GRAIN EXPLOSIVES COMPANY, OF WILMINGTON, DELAWARE, A CORPORATION OF DELAWARE.

PROCESS OF AND APPARATUS FOR FORMING EXPLOSIVE POWDER INTO SPHERICAL GRAINS.

1,162,757.

Specification of Letters Patent.

Patented Dec. 7, 1915.

Application filed July 31, 1915. Serial No. 42,983.

To all whom it may concern:

Be it known that I, ERNEST DU PONT, a citizen of the United States, residing at Wilmington, county of New Castle and State of Delaware, have invented a new and useful Improvement in Processes of and Apparatus for Forming Explosive Powder into Spherical Grains, of which the following is a full, clear, and exact description, reference being 5 had to the accompanying drawings, which form a part of this specification.

The object of my invention is to improve the known method of manufacturing granular black powder into approximately spherical grains so as to substantially increase the 10 product.

In a process patented by Francis I. du Pont and myself August 4, 1914, No. 1,106,087, the explosive is prepared in the form of a somewhat 15 pasty mass, which is then divided into separate particles, which are rolled upon a heated surface until they are dry. An efficient apparatus for practising said process is described in said patent, said apparatus 20 having been patented by said Francis I. du Pont on the same date, No. 1,106,138.

In this apparatus, the specific means disclosed for rolling and drying the particles is an inclined rotary cylinder with heated 25 walls. Said process and apparatus is practicable, efficient and successful, but care must be taken not to deliver the powder too rapidly into the rounding and drying cylinder, as otherwise the grains are apt to become 30 soft and coalesce into masses. In other words, the practicable capacity of the grain-forming mechanism substantially exceeds 35 the capacity of the rounding and drying mechanism.

40 The object of my invention is to substantially increase the capacity of the rounding and drying mechanism, in order that the output of the apparatus as a whole may be substantially increased and with a view, 45 also, of overcoming all tendency of the grains to soften and mass.

The invention will be best understood by first referring to and explaining the accompanying drawings, which show a preferred 50 form of improved apparatus for carrying out the improved process.

Figure 1 is a side view partly in section,

of a part of the apparatus. Fig. 2 is a side view, partly in section, showing, partly diagrammatically, the remaining portion of the 55 apparatus (shown partly in end view in Fig. 1).

The explosive ingredients, in the form of a pasty mass, as explained in the above mentioned patents, are introduced into a rotary 60 hopper *a* within which is a vertical revoluble shaft *b* having propeller blades *c* cooperating with stationary blades *d* projecting from the inner wall of the hopper, whereby the material is forced down toward 65 the open bottom of the hopper. On the lower end of the shaft are inclined blades *h*, which press the material into holes *i* in a flat horizontally-extending revoluble annular rim *j* of a wheel *j* in a vertical axis. The 70 holes *i* extend entirely around the wheel near its periphery. A stationary plate or guard *o* underlies the part of the wheel which at any given moment is beneath the hopper mouth and prevents the powder being forced out of the holes. A wheel *p* turns 75 on a horizontal axis within a vertical plane extending radially of the axis of the wheel *j* and has on its periphery a number of ejectors *q* which engage the holes in a manner somewhat similar to that in which a sprocket wheel engages a sprocket chain and force the plugs of powder within the holes to the lower edge thereof, a knock-off, preferably in the form of a moving thread *t*, 80 effecting the complete detachment of the plugs. The foregoing apparatus is the same as that more fully described in said patents.

In the apparatus of said patents, the detached plugs fall into a hopper, whence they 90 pass into an inclined rotary rounding and drying cylinder having steam jacketed walls, similar to the vessel *w* shown in Fig. 2. In my improvement, however, another step—that of preliminarily slightly drying the 95 surface of the grains—is interposed in the process, which step I prefer to carry out by means of the mechanism, shown in Fig. 2, interposed between the ejectors and the cylinder *w*.

100 *w* represents an endless horizontally disposed conveying belt, which is arranged to travel slowly, one end thereof being arranged under the knock-off *t* and the other

end thereof projecting into one end of the cylinder *w*; whereby the powder plugs are conveyed to the cylinder from the point where they drop from the wheel *j*. In the 5 path of travel of the plugs are a series of stationary projections *y*. A hood *z* overlies any desired part of the length of the conveyor forming a drying chamber into which hot air may be delivered from a pipe *z'*. 10 The projections *y* are shown as supported from the hood *z*. As the powder travels along the belt, the grains are turned over by the projections, thus exposing all sides of the grains to a drying action. In the 15 cylinder *w* the plugs are rounded and the drying operation is completed. The length of time the powder should undergo this treatment will vary according to the amount of powder which is delivered to the belt. The 20 following example may be given: With a delivery of 200 pounds an hour, an exposure to a drying atmosphere, preferably a heated atmosphere, of about six or seven minutes has the effect of obviating the possibility 25 of coalescence of the grains, thus permitting the cylinder *w* to effectively handle a much larger quantity of powder than would otherwise be the case.

Having now fully described my invention, 30 what I claim and desire to protect by Letters Patent is:

1. The process of forming explosive powder into grains whose shape tends to be spherical, which consists in dividing a pasty mass of the explosive into separate particles, then exposing the particles to a preliminary surface-drying operation, and then simultaneously heating and agitating the same.
2. The process of forming explosive powder into grains whose shape tends to be spherical, which consists in dividing a pasty mass of the explosive into separate particles, then exposing the particles to a preliminary drying action, and then rolling the particles 45 upon a heated surface.
3. The process of forming explosive powder into grains whose shape tends to be spherical, which consists in dividing a pasty mass of the explosive into separate particles 50 of non-spherical shape, then drying the surfaces of the particles, and then rolling the particles upon a heated surface.
4. The process of forming explosive powder into grains whose shape tends to be spherical, which consists in dividing a pasty mass of the explosive into separate particles 55 of cylindrical shape, then drying the surfaces of the particles, and then rolling the particles upon a heated surface.
5. The process of forming explosive powder into grains whose shape tends to be spherical, which consists in dividing a pasty mass of the explosive into separate particles, then subjecting the particles to a preliminary drying operation and turning over 60

the particles to expose all sides thereof to the drying action, and then rolling the particles upon a heated surface.

6. The process of forming explosive powder into grains whose shape tends to be spherical, which consists in dividing a pasty mass of the explosive into separate particles, then subjecting the particles to the action of heated air to preliminarily surface-dry them, and then rolling the particles upon a 70 heated surface.

7. The process of forming explosive powder into grains whose shape tends to be spherical, which consists in dividing a pasty mass of the explosive into separate 80 particles of cylindrical shape, then subjecting the particles to the action of heated air and turning over the particles to expose all sides thereof to the drying action, and then rolling the particles upon a heated surface 85 and continuing to roll them thereon until they are dry.

8. The process of forming explosive powder into grains whose shape tends to be spherical, which consists in dividing a pasty 90 mass of the explosive into separate particles of non-spherical shape, then subjecting the particles to a surface drying action while maintaining them in substantially the same shape, and then rolling them upon a heated 95 surface to change them into an approximately spherical form and at the same time thoroughly dry them.

9. In a machine for forming explosive powder into grains whose shape tends to be spherical, the combination with means 100 adapted to separate the explosive into separate particles, of means to surface-dry the particles, and means presenting a moving heated surface to form the particles into 105 balls.

10. In a machine for forming explosive powder into grains whose shape tends to be spherical, the combination with means adapted to separate this explosive into separate particles of non-spherical shape, of means to preliminarily dry the particles, and means presenting a moving heated surface to complete the drying of the particles and form them into balls. 110

11. In a machine for forming explosive powder into grains whose shape tends to be spherical, the combination with means adapted to separate the explosive into separate particles of cylindrical shape, of means 120 to superficially dry the particles, and means presenting a moving heated surface to round off, and complete the drying of said particles.

12. In a machine for forming explosive 125 powder into grains whose shape tends to be spherical, the combination with means adapted to separate the explosive into separate particles, of a drying chamber, a conveyor to carry said particles through the 130

drying chamber, and means presenting a moving heated surface to receive the particles and shape them into approximately spherical form.

- 5 13. In a machine for forming explosive powder into grains whose shape tends to be spherical, the combination with means adapted to separate the explosive into separate particles, of an apparatus for drying 10 and rounding the particles, and means interposed between said means and apparatus to preliminarily dry the particles and turn them over to expose all sides thereof to the surface-drying action.
- 15 14. In a machine for forming explosive powder into grains whose shape tends to be spherical, the combination with means adapted to separate the explosive into separate particles, of a drying chamber, a conveyer 20 to carry said particles through the drying chamber, projections adapted to arrest the travel of the particles and turn them over, and an apparatus for finally drying and rounding the particles.
- 25 15. In a machine for forming explosive powder into grains whose shape tends to be spherical, the combination with means

adapted to separate the explosive into separate particles, of an apparatus for drying and rounding the particles, a conveyer to 30 carry the particles from said means to said apparatus, and a dryer causing heated air to pass over the particles during their passage to said apparatus.

16. In a machine for forming explosive 35 powder into grains whose shape tends to be spherical, the combination with means adapted to separate the explosive into separate particles of cylindrical shape, of an endless conveyer to carry the particles so 40 formed, an open-bottomed drying chamber under which said conveyer travels, a pipe through which heated air is admitted to said chamber, projections in said chamber to arrest the travel of the particles and turn them 45 over, a revolute inclined cylinder whose upper end communicates with the discharge end of the conveyer, and means to heat the inner wall of the cylinder.

In testimony of which invention, I have 50 hereunto set my hand, at Philadelphia, on this 30th day of July, 1915.

ERNEST DU PONT.
